UNITED STATES PATENT OFFICE

1,994,883

AUTOMATIC SELF CLOSING STAIR

Harrington Chambers, Flushing, N. Y.

Application September 4, 1931, Serial No. 561,097

9 Claims. (Cl. 228—50)

This invention relates to stair constructions and is directed more particularly to improvements on the stair installation described and claimed in my Patent, No. 1,815,048, dated July 21, 1931. In 5 that patent, the stair construction disclosed is adapted to be associated with a well in an upper floor and is adapted to be let down into a position to provide communication between the floors and to be shifted upwardly to lie wholly above 10 the upper floor and to be concealed when in this latter position by a trap door in the well opening. In said construction, the stair is counterbalanced to facilitate its manual manipulation and the counterbalancing means is such that the stair 15 will be maintained by gravity in its lowered operative position and has to be raised by manual force into its inactive or concealed position.

In contradistinction to my prior construction, the stair of the present invention is so constituted 20 that it is automatically self closing, and when lowered into its operative position serves to energize means which tends to return it to its raised position. Means is, however, provided which 25 serves to lock the stair in its lowered position until manually released whereupon the stair will be automatically raised and moved into concealed position, there being mechanism provided to 30 check its movement into final position and to thereby preclude shock due to its automatic operation.

Aside from the broad automatic self closing feature to which I have referred, the invention embodies numerous other features which will be 35 hereinafter more fully explained and set forth in the claim.

An important feature of the present invention resides in the fact that the stair may be lowered with a minimum expenditure of physical effort, but that it is raised into concealed position in a 40 wholly automatic manner when the locking means associated therewith is manually released.

A further important feature of the present invention is inherent in certain adjusting devices 45 which permit of accurate regulation of the tension of the springs associated with the stair in such manner as to insure smooth and efficient operation.

Features of the invention, other than those 50 specified, will be apparent from the hereinafter detailed description and claims when read in conjunction with the accompanying drawings.

The accompanying drawings illustrate one 55 practical embodiment of the invention, but the construction therein shown is to be understood as illustrative, only, and not as defining the limits of the invention.

Figure 1 is a side elevation of stair construction embodying the present invention, certain 60 parts being shown in section in the interest of

clearness. In this view, the stair is shown as lowered to permit access between upper and lower floors.

Figure 2 is a view similar to Figure 1, but showing the stair in raised, concealed position. 5

Figure 3 is an enlarged fragmental detail of the structure as shown in Figure 2, showing the attachment of the stair to the trap door.

Figure 4 is a section on the line 4—4 of Figure 3.

Figure 5 is a section on the line 5—5 of Figure 2. 10

Figure 6 is a vertical section through the upper end of the stair showing the stair partially raised.

Figure 7 is a section through the stair well of the upper floor showing the anchorages for the tension means and associated sheaves situated 15 at this point.

Figure 8 is a section on the line 8—8 of Figure 7.

Figure 9 is a plan view of one of the adjusting devices shown in Figure 7. 20

Referring to the drawings, 1 designates an upper floor and 2 a lower floor between which communication is desired by the stair of this invention. The upper floor is provided with a stair well opening having a suitable jamb 3. 25

The well opening is adapted to be closed from below by a trap door 4 hinged to the jamb 3 by means of hinges 5. The trap door 4 has spaced from its lateral edges longitudinally extending stiffeners 6 and is adapted to be moved on the hinges 5 from a position where it closes the well opening, downwardly into a position to open said opening. Extending across the jamb 3 of the well opening above the door 4 is a shaft 7, the opposite ends of which are permanently secured by brackets 8, which are screwed to the jamb as indicated at 9. On this shaft are mounted two rollers 10 and with these rollers are adapted to cooperate the stringers of the stair. These stringers are indicated at 11. There are two of them and they are spaced apart by treads 12, which extend between them. Risers may be provided if desired, but ordinarily they are preferably omitted. 30

The stair may have a bannister or railing 13 supported by posts 14 rigidly secured to the stringers. The stringers 11 are adapted to rest upon the two rollers 10, rubber tired, if desired, as indicated in Figure 6 and with each of these rollers is associated a bracket 15 having inner 40 and outer flanges 16 and 17, which overlap the lower edges of the stringers as shown in Figures 5 and 6, so that the flanges 16 are adjacent to and may engage the inner face of the stringers, while the flanges 17 engage the outer face, and these flanges thus serve to preclude lateral movement of the stringers with respect to the rollers 10 and insure that the stringers ride upon these rollers at all times. 45

The stair may have a bannister or railing 13 supported by posts 14 rigidly secured to the stringers. The stringers 11 are adapted to rest upon the two rollers 10, rubber tired, if desired, as indicated in Figure 6 and with each of these rollers is associated a bracket 15 having inner and outer flanges 16 and 17, which overlap the lower edges of the stringers as shown in Figures 5 and 6, so that the flanges 16 are adjacent to and may engage the inner face of the stringers, while the flanges 17 engage the outer face, and these flanges thus serve to preclude lateral movement of the stringers with respect to the rollers 10 and insure that the stringers ride upon these rollers at all times. 50

One of the brackets 15 and the corresponding roller 10 is precluded from longitudinal movement 55

60

on the shaft 7 by cotter pins 18, as shown in Figure 5, although the other roller with its bracket may be free to move longitudinally of the shaft to compensate for slight variations in width of the stair. The flange 17 of each of these brackets is, however, provided with an elongated follower 19 adapted to extend into a slot 20 formed on the outer face of each stringer and through the cooperation of these parts the stringer is precluded 10 from lifting off of the associated roller 10. The followers 19 are elongated as shown, so as to preclude binding during the operation of the stair.

The main portion of the weight of the stair is carried by the shaft 7 through the rollers 10, but 15 the stair is also operatively connected to the trap door 4, so that the trap door and the stair will pivotally move together. To this end, the trap door is provided near its free end with a shaft 21 extending transversely between the stiffeners 6 20 and secured thereto by fixtures 22. On this shaft 21 are mounted brackets. Each bracket comprises two plates 23 and 24, the former of which is on the inside of the stringer and the latter of which is on the outside of the stringer, and these two 25 plates overlap the lower margin of the stringer, as shown in Figs. 3 and 4. Between each of the plates 23 and 24, are pivoted two rollers 25 on which the lower edge of the corresponding stringer rides, and the plate 24 carries an elongated follower 30 26 which works in the guide slot 20 of the stringer. A corresponding arrangement is provided for each stringer.

By this arrangement, the stringers are adapted 35 to ride on the rollers 25, and although the plates 23 and 24 are pivotal with respect to the shaft 21, the double rollers 25 and the elongated follower 26 preclude cramping due to different angular relations between the stair and the trap door and thus provide for a smooth, silent and free running operation. The part 27 shown in Figure 3 40 is a member of resilient material, one of which is mounted adjacent the lower end of each stringer, so that as the stair is slid in an upward direction, these bumpers will engage with the plates 45 24 and form stops to such upward movement without appreciable shock or jar.

By virtue of the mounting of the stair on the rollers 10 of the shaft 7 and the rollers 25 of the shaft 21, the stair is mounted for substantially 50 anti-friction longitudinal movement whereby it is adapted to be moved upwardly and then pivotally into the position of Figure 2 and returned from this position into a position of Figure 1. In order that the movement of the stair may be 55 properly counterbalanced and effectually controlled, there is associated with the stair appropriate counterbalancing and operating means next to be described. Mounted at the sides of the well on the jamb 3 and at the end thereof distant from the shaft 7, are two brackets 28, one of which is positioned at each side of the well and is firmly 60 screwed thereto in a rigid manner. Each of these brackets carries a sheave 29, which is lined up with a sheave 30 on the shaft 7, there being a sheave 30 adjacent each end of this shaft. Two long helical springs 31 are anchored to fittings 32 adjacent each lateral edge of the trap door 4 and near its free end. These springs extend upwardly over the sheaves 29, thence to and about the sheaves 30 and thence forwardly in the direction of the brackets 28 where their ends are anchored. The ends of these springs are not directly anchored to the brackets 28, but are secured thereto through intermediate regulating 75 means shown in detail in Figures 7, 8 and 9. In

these figures, each bracket 28 is shown as having a stud 32' which extends outwardly to a point in line with the sheave 29. To the outer end of this stud is pivotally secured a link 33 having therein a series of perforations 34. The link is adapted to extend into the interior of the associated spring 31 and the adjacent end of the spring is coiled to provide a fastening means for a loop member 35 through the perforated ends of which a bolt 36 is adapted to be passed and this bolt may be associated with any one of the perforations 34 as may be found necessary to impart the desired tension to the spring.

Both of the springs 31 are connected to their corresponding brackets 28 in the manner described. The upper ends of the brackets 28 are connected by a rod 37 and to this rod is connected two links 38, which are identical with the links 33, except that their ends are twisted and are lined up with sheaves 39 on the shaft 7. To the 20 links 38, springs 40 are adjustably secured in the same manner as the springs 31 are secured to the studs 32'. These springs extend from the links 38 about the sheaves 39 and thence longitudinally along the sides of the stringers to a point adjacent the lower end of the stringers where they are anchored to brackets 41.

It will be noted from Figure 5 that the cotter pins 42 serve to preclude shifting of the sheaves 30 and 39 longitudinally of the shaft 7, this arrangement being duplicated at both ends of the shaft.

It will be noted from the description of the parts as thus far advanced that the springs 31 serve to counterbalance the weight of the door 35 and stair in a substantially vertical direction, while the springs 40 serve to counterbalance the weight of the stair in a longitudinal direction. In accordance with the present invention, the stair will tend normally to longitudinally elevate 40 unless locked in lowered position.

In order to preclude inadvertent closing of the stair, I provide locking means next to be described. The top step or tread 43, as shown in Figure 6, extends across the upper ends of the stringers 45 which are cut on a miter, so that the tread 43 will be horizontal when the stairs are lowered. This tread is supported on the stringers by means of fittings 44 which are preferably stamped up from sheet metal and are so formed as to serve 50 as either rights or lefts. Each of these fittings is provided therein with two recesses 45 which are lined up with pins, one of which is lined up with a pin 46 mounted on one of the brackets 15. Adjacent the recess 45 which is lined up with the 55 pin 46 is a pivot 47 to which is pivotally secured a latch 48, the lower end of which is curved to form a cam face 49, terminating in a cutout 50, complementary to the recess 45. The latch 48 normally gravitates into a position to close the 60 outlet of the recess 45, with the cam face 49 lined up with the pin 46.

When the stair is lowered, it slides longitudinally of the bracket 15 until it reaches its lowermost position, whereupon the cam face 49 will 65 engage with the pin 46 to cause the latch to be swung upwardly into the dotted line position of Figure 6 to permit the pin to enter the recess 45 upon the advent of which the latch will fall into the full line position, thereby locking the pin in 70 the recess. By this arrangement, the stair is locked in lower position and although the tendency of the springs is to lift the stairs, this cannot occur until the latch is released. The release of the latch is accomplished by means of a trip lever 75

51 having a slot 51', pivoted at 52 on the fitting 44 and having associated therewith a pull cord or chain 53 which, when manually operated, will lift the latch into the dotted line position of 5 Figure 6, and leave the stair free for operation by the springs as stated. A spring 49a assists gravity in maintaining the latch in locking position. Slot 51' precludes the lever 51 and the latch 49 from binding during operation.

10 During the operation of the stair, my experience has shown that there is a tendency of the springs 40 to strike against the stiffeners 6 and produce noise. This is obviated by providing two or three 15 felt or rubber silencing strips 54 on the outer face of each stiffener 6.

Practical experience with the structure of the character described has fully demonstrated its efficiency. The parts may be so adjusted that very little manual effort is required to lower the 20 stair, this being accomplished by a downward pull on a pull chain 55 secured to the trap door as shown in Figure 1. The pull chain is pulled downwardly until the stair is within convenient reach whereupon the stair is grasped and easily 25 drawn downward until it reaches its lowermost position whereupon the latch 48 automatically locks it in place. The parts remain in this position until it is desired to raise the stair, whereupon the pull cord 53 which is of convenient access 30 is pulled to release the latch and the stair thereupon is automatically elevated by the springs. In order to provide for relatively quick closing without jar or shock when this operation is completed, I associate with the door any appropriate 35 snubber or door check arrangement indicated generally by the reference character 56, so that as the door nears closed position, the check comes into operation to slow down its movement in order that it may finish such movement slowly and 40 without shock or jar.

The structure of this invention is simple, economical and thoroughly efficient for the performance of its intended functions. It eliminates the necessity of lifting the stairs when it is desired to close the same and for the first time 45 provides a self closing stair of the character under consideration. When the stair is down, the weight of the stair and door will overbalance the tension of the springs 31, so that the stair will rest firmly on the floor and will not tend to shift. The tension of springs 40, however, is such 50 that they overbalance the weight of the stair in a longitudinal direction and tend to lift the same, but latch 48 locks the stair against this movement. When the latch is released the stair is 55 immediately and automatically moved upwardly in a longitudinal direction by the springs 40. As the stair is raised, the weight of the stair imposed upon the door is progressively diminished to permit the springs 31 to come into operation to 60 overbalance the weight of the door and stair in a vertical direction with the result that the stair is pivoted into substantially horizontal position and the door is closed.

65 In practice these operations occur progressively and the tensions of the several springs coact in such manner that during the shifting of the center of weight of the stair, the springs 31 smoothly enter into the operation and thereafter 70 cooperate with spring 40 to move the parts into final position noiselessly and without shock, jar or vibration.

The foregoing detailed description and the accompanying drawings show the invention in its preferred, practical form. I am aware, however,

that the invention is capable of modification without departing from the spirit or scope of the appended claims which are to be construed in this light.

In practice, I find it desirable to mount the cross rod 37 somewhat lower than shown in the drawings and sufficiently close to the sheaves 29 to retain the springs 31 in said sheaves, so that they cannot be inadvertently displaced or shift off the sheaves. Similarly, the sheaves 30 and 39 are placed sufficiently close to the jamb 3, as shown in Figure 1, and the springs 31 and 40 are retained by said jamb in said sheaves.

Having thus fully described the invention, what I claim as new and desire to secure by Letters Patent is:

1. In a stair construction adapted to be used between lower and upper floors, the latter of which is provided with a stair well opening, a trap door adapted when in horizontal position to close the opening and which door is hinged to be opened into a downwardly inclined position, a shaft rigidly mounted to extend across the well opening near one end thereof, spaced apart rollers on said shaft, brackets associated with said rollers, similarly spaced rollers and associated brackets near the free end of the door, a rigid stair mounted to rest on said rollers and engage with the corresponding brackets and to slide longitudinally thereon and to move pivotally when the door is pivoted moved, one of the rollers and the corresponding bracket on said shaft being fixed against movement longitudinally of the shaft and the other roller and the corresponding bracket being adapted for longitudinal adjustment on the shaft to compensate for variations in stair width, lifting means tending to impel the stair in a longitudinal upward direction, lifting means tending to close the door as the stair is elevated, locking means for locking the stair in a lowered position with the door opened, and means for releasing the locking means to permit the lifting means to elevate the stair and close the door.

2. In a stair construction adapted to be used between lower and upper floors, the latter of which is provided with a stair well opening, a trap door adapted when in horizontal position to close the opening and which door is hinged to be opened into a downwardly inclined position, a shaft rigidly mounted to extend across the well opening near one end thereof, spaced apart rollers on said shaft, pivoted brackets mounted adjacent the free end of the door and similarly spaced, a plurality of rollers on each of said brackets, a rigid stair having treads and stringers with the stringers positioned to rest upon and longitudinally travel on the rollers of the shaft opening near one end thereof, spaced apart rollers and brackets, the stringers being provided on their outer faces with guides, an elongated follower carried by each of said brackets and cooperating with the guides to hold the stringer in contact with the rollers of said brackets, the rollers of the door brackets being spaced apart on opposite sides of the vertical axial plane of the pivot of each bracket to preclude binding of said followers in said guides, brackets carried by the shaft and having followers also engaging with the guides of the stringers to hold the stringers in engagement with the rollers of the shaft, springs tensioned to close the door when the stair is elevated, additional springs tensioned to elevate the stair through the well opening, so that the door can be closed, and means for locking the stair in lowered position with the door

open; said means being releasable to allow the springs to elevate the stair and close the door.

3. In a stair construction adapted to be used between lower and upper floors, the latter of which is provided with a stair well having a hinged trap door therein, a rigid stair mounted for sliding movement longitudinally of the door, springs anchored to the stair and to the door and also anchored with respect to the upper floor, the anchorages of the springs to the upper floor comprising adjustable links, whereby the tension of the springs may be regulated, and directional sheaves coacting with the springs to impress the tension of the springs on to the door and stair, so as to cause the stair to be elevated and the door to be closed when the stair is elevated, means for locking the stair in lowered position with the door open, and means for releasing the locking means to permit the springs to lift the stair and close the door.

4. In a stair construction adapted to be used between lower and upper floors, the latter of which is provided with a stair well opening having a hinged trap door therein, guide rollers mounted near the free end of the door, a shaft extending uninterruptedly across the well opening at the end thereof at which the door is hinged and which shaft is supported at its opposite ends on the jamb on opposite sides of said well opening, rollers carried by said shaft, a rigid stair embodying stringers and treads mounted with the lower edges of the stringers bearing upon the rollers on the door and shaft to mount said stair for longitudinal movement, helical coil springs secured to the stair and jamb for counterbalancing the weight of the stair in the direction of its length, and helical coil springs, separate from and independent of the said coil springs of the stair and jamb, secured to the jamb and door for counterbalancing the weight of the door and stair in a substantially vertical direction, whereby the stair is counterbalanced in the direction of its length independently of its counterbalancing in a substantially vertical direction, means for tensioning said springs to provide therein sufficient tension to elevate the stair and thereupon close the door, and means for locking the stair in lowered position with the door open against the tension of said springs, said last mentioned means being releasable to permit the stair to be lifted and the door closed by said springs.

5. An adjustable connector for securing one end of a coil spring to an anchorage including a coil spring, said connector comprising a rod having at one end an attaching member and provided with perforations spaced longitudinally thereof, a loop member adapted to engage with the coil of the spring, and a bolt passing through said loop member and adapted to be passed through any one of said perforations.

6. In a stair construction adapted to be used between lower and upper floors, the latter of which is provided with a stair well opening, a trap door adapted when in horizontal position to close the opening and which door is hinged to be opened into a downwardly inclined position, a rigid stair embodying stringers and treads, means for mounting the stair for longitudinal movement in the direction of its length through the well opening and for pivotal movement with the door, helical springs for counterbalancing the weight of the stair in the direction of its length and the weight of the door and stair in a substantially vertical direction, said springs being

sufficiently strong to normally tend to elevate the stair in the direction of its length and thereupon pivotally close the door, locking means for locking the stair against upward movement in the direction of its length under the tension of the springs, manually operable means for releasing said locking means to permit the stair to be elevated, whereby, with an accompanying upward movement of the center of weight of the stair, the door may be closed under the tension of the springs, and means for checking the closing movement of the door and concurrent pivotal movement of the stair to preclude slamming of the door when the stair is in fully elevated position.

7. A stair construction adapted to be used between lower and upper floors, the latter of which is provided with a stair well opening having a hinged trap door therein, a rigid stair slidably secured to the door for movement in the direction of its length and embodying stringers and treads, lifting means for normally impelling the stair upwardly in the direction of its length and for thereupon pivotally impelling the door into closed position, means for locking the stair against upward movement in the direction of its length under the power of the lifting means, means for releasing said locking means to permit the stair to move upwardly in the direction of its length with an accompanying upward movement of the center of weight of the stair, and means for slowly dissipating the upward momentum of the stair and door as they approach the upward termini of their respective travels to cushionably bring them to a state of rest with the door in closed position.

8. A stair construction adapted to be used between lower and upper floors, the latter of which is provided with a stair well opening having a hinged trap door therein, a rigid stair slidably secured to the door for movement in the direction of its length and embodying stringers and treads, lifting means for normally impelling the stair upwardly in the direction of its length and for thereupon pivotally impelling the door into closed position, and means for slowly dissipating the upward momentum of the stair and door as they approach the upward termini of their respective travels to cushionably bring them to a state of rest with the door in closed position.

9. In a stair construction adapted to be used between lower and upper floors, the latter of which is provided with a stair well opening having a trap door, a rigid stair mounted for longitudinal sliding movement upwardly and downwardly in the direction of its length through the well opening and for pivotal movement during such sliding movement, lifting means of sufficient strength to normally lift the stair into a position above the ceiling of the lower floor and close the door, means to lock the stair in lowered position against the power of the lifting means, after the stair has been lowered, manually operable means to release said locking means and thereby render the stair responsive to the power of the lifting means, whereby said stair will be automatically lifted to a position above the ceiling of the lower floor and the door closed, and means for slowly dissipating the upward momentum of the stair and door as they approach the upper terminal of their respective travels to cushionably bring the stair and door to a state of rest without shock or jar.
